SPRAY GUN

Filed July 19, 1938

FIG. 1.

UNITED STATES PATENT OFFICE

2,208,464

SPRAY GUN

Abraham Isaac Logette and Edgar Harry Dainton,
London, EnglandApplication July 19, 1938, Serial No. 220,070
In Great Britain July 21, 1937

5 Claims. (Cl. 299—140)

This invention relates to apparatus for spraying liquids such as oils, paints, varnishes and so forth, under pressure, of the kind known as spray guns, and has for its object to provide such spray guns with a new and improved measured quantity delivery device which enables the volume of liquid to be sprayed at each operation of the gun to be accurately controlled and indicated to the operator.

10 The present invention is particularly applicable to spray guns such as those employed for spraying mixtures of oils and other liquids and anti-corrosive solutions into the cylinders of aeroplane and other engines to form a protective film and enables the volume of the sprayed liquid at each operation of the gun to be accurately determined and indicated to the operator.

15 Spraying guns of the kind referred to are provided with a connection to the source of liquid 20 to be sprayed which is stored at suitable pressure and with a valve controlled connection with an air compressor or other suitable source of motive fluid, the liquid to be sprayed being delivered to the gun under compressed air or 25 other pressure and forced through the spraying head by the compressed air or other motive fluid, the supply of which is regulated by the compressed air or other motive fluid valve controlled by the operator.

30 According to this invention a gun for spraying liquids under pressure is provided with a measured quantity delivery and indicating apparatus that is connected through an inlet valve with the supply of liquid to be sprayed and also through 35 an outlet with the spraying head or nozzle of the gun so that the measured quantity delivery apparatus can be charged under pressure with the liquid to be sprayed and forms the reservoir from which such liquid is supplied under pressure 40 to the spraying head through which it is sprayed in known manner by the compressed air or like motive fluid controlled by the operator, while means are preferably provided for by-passing or rendering inoperative the measured quantity delivery apparatus so as to enable the gun to be used for spraying liquid independently thereof.

45 The measured quantity delivery and indicating apparatus comprises a cylinder of predetermined capacity formed or arranged upon the body of the spray gun, a pressure controlled piston which works fluid tight therein and an adjustable liquid supply valve through which the cylinder is charged under pressure with the liquid to be sprayed.

50 55 The cylinder is furnished at one end with inlet

and outlet passages for the liquid to be sprayed and is closed at its other end by a perforated cover through which works a piston rod mounted upon the piston that works in such cylinder.

5 The adjustable liquid supply valve is mounted in a housing formed or arranged upon the body of the spray gun, which housing is connected with the inlet passage of the cylinder and also with the liquid supply system of the spray gun through the inlet valve mounted therein, which 10 valve is spring controlled and furnished with an operating lever while the liquid outlet passage of the cylinder is connected with the delivery tube of the spray gun which tube is normally closed in known manner by a spring controlled delivery valve through which it is connected to the spraying head of the gun.

15 The rod of the piston that works within the cylinder serves to indicate the volume of liquid admitted to and discharged from the cylinder. 20 For this purpose such rod may be furnished with a suitable scale or it may cooperate with an adjustable stop mounted upon a graduated guide arranged externally of the cylinder.

25 The piston of the measured quantity delivery apparatus may be spring controlled, alternatively such piston may be controlled by compressed air admitted to the cylinder through an air passage connected with the compressed air-circulating 30 passages of the spray gun.

35 Such compressed air passages are controlled by a normally closed air valve which is connected through such passages on one side with a source of compressed air and on the other side with the spraying head of the gun through passages arranged concentrically of the liquid delivery tube, which latter is interconnected with the concentric air passages so that when the gun is operated the liquid is sprayed through such head by the compressed air.

40 The spray gun is operated through its main operating lever which is connected with the liquid delivery valve and arranged relatively to the air valve so that both valves are operated together by the lever. The liquid to be sprayed is 45 delivered from the cylinder by the pressure-controlled piston mounted therein past the liquid delivery valve as the latter is opened, while compressed air passes the air valve through the air passages to the spraying head in which it mingles 50 with the liquid and sprays the same therethrough.

55 The invention is further described with reference to the accompanying drawing wherein similar references indicate like parts.

Fig. 1 is a longitudinal sectional view of a spray gun furnished with a measured quantity delivery apparatus in accordance with the present invention. Fig. 2 is an external plan view of the construction illustrated in Fig. 1 with parts broken away for the purposes of illustration. Fig. 3 is a detail sectional view illustrating a slightly modified construction of the measured quantity delivery apparatus and Fig. 4 a sectional view illustrating a further modification thereof presently referred to.

Referring to the drawing, in the constructions illustrated the cylinder 1 and the valve housing 2 of the measured quantity delivery apparatus are formed integrally with the body 3 of the spray gun. One end of the cylinder is connected by an inlet passage 4 with the valve housing and also by an outlet passage 5 with the liquid delivery tube of the spray gun, presently referred to.

20 A piston 6 furnished with a piston rod 7 is slidably mounted in the cylinder 1, the outer end of which is closed by a perforated cover 8 through which the piston rod works, such cover having an externally threaded flange 8a which screws 25 into the internally threaded outer end of the cylinder.

The piston 6 is furnished on its inner side with a cup leather 6a which makes a sliding fluid tight joint with the interior of the cylinder and is secured on the reduced screw threaded end of the piston rod 7a by a washer 6b and nut 7b.

In the construction illustrated in Fig. 1 the piston is controlled by the pressure of two coiled springs which are mounted upon the piston rod 35 so as to bear between the piston 6 and the perforated cylinder cover 8 while the reduced end 7a of the piston rod is adapted to abut the inner end of the cylinder so as to limit the inward movement of the piston therein.

40 The cylinder cover 8 is formed with an external graduated rack 11 of channel cross-section, the side walls 12 of which have regularly spaced notches 11a formed therein which are indexed to form a volumetric scale and are adapted to 45 receive an adjustable stop 12a. Such stop consists of a cross-bar mounted in the limbs of a fork 13 that comprises a socket 14 in which a spring controlled bullet catch 15 is mounted so as to bear on the underside of the rack and hold 50 the stop in engagement therewith.

The cylinder 1 is made of pre-determined capacity and the scale of the rack 11 calibrated therewith so that the movements of the piston rod over such scale indicate the volume of liquid 55 admitted or displaced by the corresponding movements of the piston 6 in the cylinder.

The valve housing 2 is furnished with a coned liquid supply valve 16 which controls an inlet passage 2a in such housing and is provided with 60 a spindle 16a and a grooved guide 17. Such valve is controlled by a coiled spring 18 mounted upon its spindle between the guide 17 and the stuffing box 19 secured in the upper end of the housing by a perforated screw gland 20 through 65 which the valve spindle projects and works. The outer end of the valve spindle is screw threaded and passes through the perforated arm 21 of an operating lever 22 in which the valve spindle is adjustably retained by nuts 21a while the lever 70 22 is pivotally mounted upon a spindle 23 in bearings 23a formed on the exterior of the valve housing.

The body 3 of the spray gun comprises as usual a piston grip extension 3a and a barrel 24 in which 75 a liquid delivery tube 25 is mounted concentri-

cally so as to form an annular space 24a in the barrel.

As shown, the delivery tube is screwed into a reduced internally threaded extension 24b of the barrel, while its outer end is furnished with a nozzle piece 26 that forms a housing for a coned liquid delivery valve 27, controlled by a coiled spring 28 so that it normally closes the vent of the nozzle piece.

The outer end of the gun barrel 24 is furnished with an externally threaded coupling tube 29 one end of which is secured fluid tight therein by a nut 29a and packing 29b while its other end carries an adjustably mounted internally threaded union nut 30 which is adapted to connect the delivery pipe 31 that leads to the spraying head 32. In the construction illustrated the delivery pipe 31 is of light metal and is provided with an internal liquid outlet pipe 33 of small diameter which is retained concentrically therein by spiders or perforated distance pieces a so as to form an annular air space about the centre pipe.

The outer delivery pipe 31 is furnished with a flange 31a at its inner end while the small inner delivery pipe 33 projects beyond the flange 31 25 to form a spigot 33a, its other end terminating within the spraying head 32 (Fig. 2) so that it intercommunicates with the terminal end of the annular air space 31a in such head.

The spigot end 33a of the liquid outlet pipe 33 30 is adapted to engage a socket 26a formed in the adjacent end of the nozzle piece 26 as an extension of the nozzle vent that is normally closed by the liquid delivery valve 27.

The liquid delivery valve is connected to the operating lever 36 of the gun by the valve rod 34 and U-shaped bridle 35. The operating lever is controlled by a spring 37 and provided with an adjustable set screw 38 for operating the normally closed spring controlled air valve 39 that 40 is mounted as usual in the body of the spray gun so as to control air passages 40 and 40a formed therein.

The air inlet passage 40 is furnished with a coupling 41 through which it is connected with 45 the compressed air supply pipe from the compressor or other suitable source of compressed air, while the air passage 40a connects the air valve with the barrel 24 of the gun.

The body of the gun is also furnished with a 50 liquid inlet passage 42 furnished with a coupling 43 by which it is connected with the supply pipe to the source of liquid to be sprayed, the inner end of which passage is connected by a liquid supply duct 42a with the inlet 2a in the valve 55 housing 2 of the measured quantity delivery apparatus, which inlet 2a is normally closed by the spring controlled liquid supply valve 16 mounted in such housing. The outlet passage 5 of the cylinder 1 is interconnected with the liquid delivery 60 tube 25 in the barrel of the gun, which tube is normally closed by the liquid delivery valve 27.

The measured quantity delivery cylinder 1 is charged under pressure with the liquid to be sprayed by operating the lever 22 of the liquid 65 supply valve 16 to allow the liquid to flow through the valve housing 2 into the cylinder and move forward the piston 6 against the resistance of its controlling spring, the liquid also priming the delivery tube 25 and nozzle piece 26, closed by 70 the liquid delivery valve 27.

As the piston moves forward the outer end of the piston rod 7 moves over the graduated rack 11 until its abuts the adjustable stop set in one or other of the rack notches, so automatically 75

limiting the forward movement of the piston and consequently the volume of liquid entering the cylinder.

To effect spraying of the liquid the lever 36 of the spray gun is operated against the resistance of its spring 37, which operation opens the liquid delivery valve 27 and simultaneously opens the air valve 39 in the gun body. As these valves are opened the liquid to be sprayed is driven from the measured quantity cylinder 1 by the pressure controlled piston 6 mounted therein through the liquid delivery system of the gun to the spraying head, while compressed air is also admitted past the air valve through the annular space 24a in the gun barrel and the restricted annular space y about the nozzle piece 26 through the annular air passage in the delivery pipe 31 to the spraying head, in which latter the compressed air mingles with the liquid and delivers the same through the spraying head as a fine spray.

The measured quantity delivery cylinder 1 is furnished with an air vent that is normally sealed by a screw plug 50 which is opened when the cylinder is being charged to allow any air trapped behind the piston and in the liquid delivery system to escape, the plug being reclosed immediately thereafter.

If desired, the measured quantity delivery apparatus may be rendered inoperative by locking the liquid supply valve 16 thereof in its open position. To effect this the nuts 21a on the outer end of the valve spindle 16a are screwed up so as to raise the spindle in the perforated arm 21 of the operating lever, which prevents the valve closing the inlet 2a of the valve housing 2. The liquid to be sprayed thus passes via the valve housing, the inlet passage 4 and outlet passage 5 of the cylinder 1 to the liquid delivery tube 25 in the barrel of the gun so that the latter can be used in the ordinary way for spraying liquid independently of the measured quantity delivery apparatus. Alternatively, the spraying apparatus may be provided with means for by-passing the measured quantity delivery apparatus, such for example as a direct connection between the liquid and delivery passages of the apparatus, such connection being controlled by a by-pass valve.

In the modification illustrated in Fig. 3 the piston rod 7 is shown furnished with a volumetric scale which registers against the outer surface of the cylinder cover 8 as the liquid to be sprayed is admitted to and discharged from the cylinder 1, this arrangement being used in place of the graduated rack and stop described with reference to Fig. 1.

In the modification illustrated in Fig. 4 the piston 6 in the measuring cylinder 1 is controlled by air pressure instead of by springs. For this purpose the perforated cylinder cover 8 is furnished with a gland and stuffing box 8c through which the piston rod 7 works fluid tight, while the cylinder 1 is provided with a compressed air inlet passage 1d which is arranged adjacent to the cylinder cover and communicates with the concentric air space 24a in the gun barrel 24. The piston 6 is provided on its front surface with an additional cup leather 6c which makes a sliding fluid tight joint with the cylinder to prevent escape of motive fluid past the piston. The piston 6 is externally grooved as indicated at 6x and furnished with a cross passage 6y which communicates with a longitudinal bore 7x formed through the piston rod 7 so that any motive

fluid leaking past the piston 6 can escape through the passage 6x, 6y and 7x to the atmosphere. In this construction, when the cylinder 1 is charged under pressure with the liquid to be sprayed, the piston 6 is moved forward and displaces air 5 trapped therein through the air passage 1d.

When the lever 36 of the spray gun is operated compressed air is supplied to the cylinder 1 in front of the piston 6 through the air passage 1d so that the piston is driven back and displaces 10 under pressure the liquid to be sprayed through the outlet passages to the spraying head, as previously described.

What we claim is:

1. The combination with a gun for spraying 15 liquids, of a measured quantity delivery and indicating apparatus comprising a cylinder of predetermined capacity furnished with liquid inlet and outlet passages, a pressure controlled piston working fluid tight in said cylinder and provided 20 with a piston rod adapted to indicate the volume of liquid admitted to and discharged from said cylinder and liquid supply valve through which said cylinder is charged under pressure with the liquid to be sprayed and an outlet passage connecting said cylinder with the liquid delivery 25 valve of the spray gun through which the liquid is delivered to the spraying head, said piston working within the cylinder being adapted to contact with an adjustable stop mounted upon a 30 graduated guide arranged externally of the cylinder so as to limit and indicate the volume of liquid admitted to and discharged from said cylinder through the spraying head.

2. The combination with a gun for spraying 35 liquids under pressure of a measured quantity delivery and indicating apparatus comprising a measuring cylinder having at its inner end an air vent furnished with a plug and liquid inlet and outlet passages through which said cylinder 40 is arranged in series with the liquid inlet and delivery system of the spray gun, said inlet passage being connected with said liquid inlet system through a normally closed spring controlled liquid supply valve and said outlet passage with 45 said liquid delivery system which is normally closed by the delivery valve of the gun and connected with the spraying nozzle, a piston working fluid tight in said measuring cylinder and furnished with a piston rod that works through 50 a perforated cover on the outer end of said cylinder, a tail rod on said piston adapted to abut the inner end of the measuring cylinder and limit the inward movement of the piston therein, a graduate guide mounted externally of said cylinder cover and a stop adjustably mounted on 55 said guide in alignment with the piston rod to limit the outward movement of said piston and rod under the influence of liquid supplied to the cylinder through said liquid supply valve, and means for supplying pressure to the piston so as to return the piston in the cylinder and force the liquid from the latter to the spraying nozzle of the gun when the latter is operated.

3. In a gun for spraying liquids under pressure 65 furnished with a measured quantity delivery and indicating apparatus according to claim 2, wherein the spring controlled liquid supply valve controlling the liquid inlet to the measuring cylinder is furnished with adjusting means whereby 70 said valve, together with the measuring and delivering apparatus, can be rendered inoperative, substantially as set forth.

4. The combination with a gun for spraying 75 liquids under pressure, of a measured quantity

delivery and indicating apparatus comprising a measuring cylinder, inlet and outlet passages at the inner end of said cylinder, arranged in series with the liquid inlet and delivery system of the gun, an adjustable spring controlled liquid supply valve in series with said liquid inlet passage, means for holding said valve open, a piston working fluid tight in said cylinder and furnished with a piston rod that works fluid tight through a perforated cover on the outer end of the cylinder, said piston being externally grooved and furnished with a transverse bore communicating with said groove and with a longitudinal bore in said piston rod, an air passage in the outer end of said cylinder adjacent the cover thereof, which passage constantly communicates with the compressed air circulating system of the spray gun so that when the latter is operated the piston is moved inwards to expel liquid from the cylinder to the spraying head of the gun, a volumetric scale on said piston rod adapted to read against the outer surface of the cylinder cover through which it works, adjustable means externally of said cover to limit the outward movement of said piston and piston rod in said cylinder, and an air vent furnished with an adjustable plug on the inner end of said measuring cylinder.

5. In a paint spray gun or the like, a pistol-

like body enclosing a piston chamber and a valve chamber and having a pistol-grip extension, a piston in said piston chamber, a piston rod carrying said piston and extending beyond the same at one side to form a stop, a spring to force said piston in the direction of the stop, said body having a port between said valve chamber and said piston chamber, a liquid inlet port to said valve chamber and a spring-loaded valve controlling said liquid inlet port, a lever for opening said valve, means to indicate the position of said piston in its cylinder, an adjustable stop to limit the movement of said piston away from the liquid inlet end of the cylinder, a liquid delivery tube in communication with the liquid inlet end of said cylinder, a spring-loaded valve normally closing said delivery tube, a compressed air duct cooperatively associated with said delivery tube, a spring-loaded valve controlling the passage of air through said compressed air duct, and a single lever means cooperatively associated with said pistol-grip extension and connected with said compressed air valve and with said delivery tube's valve for simultaneously opening both said valves.
